UNITED STATES PATENT OFFICE.

ERNEST G. DANIELSON, OF SAN FRANCISCO, CALIFORNIA, ASSIGNOR TO E. T. CUNNINGHAM, OF SAN FRANCISCO, CALIFORNIA.

RHEOSTAT.

Application filed July 18, 1921. Serial No. 485,696.

To all whom it may concern:

Be it known that I, ERNEST G. DANIELSON, a citizen of the United States, and a resident of the city and county of San Francisco, State of California, have invented a certain new and useful Rheostat, of which the following is a specification.

The invention relates to small rheostats for varying the resistance of an electric circuit, and particularly to panel type rheostats.

An object of the invention is to provide an inexpensive rheostat of simple construction.

Another object of the invention is to provide a mounting for a helical resistance element, so that air is free to circulate through the element to keep it cool.

The invention possesses other advantageous features, some of which the foregoing, will be set forth at length in the following description where I shall outline in full, that form of the invention which I have selected for illustration in the drawings accompanying and forming part of the present specification.

In said drawings:

Fig. 1 is a rear view of the rheostat mounted on a panel.

Fig. 2 is a side elevation of the rheostat.

Fig. 3 is a vertical section through the resistance element mounting.

The rheostat of my invention comprises a moulded disc 2 of bakelite or other similar dielectric which is adapted to be secured by screws to a panel 3. The disc is provided with a peripheral flange 4, curved in cross section and springing forward from the face of the disc, to form a shallow peripheral groove, in which the helically coiled resistance element 5 is disposed, and in which it is preferably adhesively secured. The resistance element projects radially beyond the edge of the disc, so that the greater portion of the wire of the resistance element is exposed over its whole surface to the air, thereby providing for maximum air cooling of the resistance element.

At one portion of its periphery the disc is provided with a boss 6, which is disposed between the ends of the resistance element.

One end of the resistance element is connected to a binding post 7 and the other end is anchored in the disc or in the boss. One wire of the circuit, the resistance of which is to be varied, is connected to the binding post 7 and the other wire is connected to the binding post 8, the binding posts consisting of screws seated in the boss.

Extending through the panel and the disc is a rod 9, having on its forward end a knob 12 and a pointer 13, which is movable over a scale on the face of the panel. Secured to the rear end of the rod is a resilient contact arm 14, which is electrically connected to the binding post 8 by a resilient metallic strip 15, held in place by the binding post 8 and having an aperture in its other end through which the rod passes, the resiliency in the strip keeping it in pressure contact with the contact arm holding nut 16. The outer end of the contact arm is bent so that the contact end 17 lies substantially tangential to the helix of the resistance element, thus providing a smooth flat surface contact. Rotation of the knob moves the contact arm over the helix to vary the amount of resistance in the circuit.

I claim:

1. In a rheostat, a circular disc having a peripheral groove, a conductor coiled in the form of a long helix held within the groove, said groove being so shallow that the major portion of the helix is exposed, and a flat resilient contact arm of a single piece of metal rotatable on an axis passing through the center of the disc, said arm having a surface contacting with the helix on a plane oblique to the axis.

2. In a rheostat, a resistance element, a contact arm rotatable to vary the point of connection between it and the resistance element, a rod, means for supporting the rod, said rod passing through the contact arm, means for fastening the arm to the rod whereby the rod may serve to rotate the arm, and means for making an electrical connection to the contact arm comprising a flat metallic spring fastened at one end to the rod support and having its free end bearing against the arm fastening means.

3. In a rheostat, a thin circular disc of insulation material, said disc having a narrow curved flange extending from one of its faces thereof to provide a circumferential groove, a conductor coiled in the form of a long helix having a diameter substantially larger than the width of the groove and held

within the groove, and a rotatable contact arm for making an electrical connection to the helix.

In testimony whereof, I have hereunto set my hand.

ERNEST G. DANIELSON.
